United States Patent Office

Des. 178,662
Patented Sept. 4, 1956

178,662

SET OF PLAYING CARDS

Victor Hofman, Brussels, Belgium

Application July 27, 1954, Serial No. 31,632

Term of patent 14 years

(Cl. D34—13)

Fig. 1.

Des. 178,662

PAGE 2

Fig. 2.

Fig. 3.

Figs. 1, 2, and 3 are face views of a set of playing cards showing my new design.

The backs of the cards are conventional.

I claim:

The ornamental design for a set of playing cards, as shown and described.
